(**) Term: **14 Years**

(57) **CLAIM**

(21) Appl. No.: **29/163,086**

A module for magnetic coupling, particularly for a toy, as shown and described.

(22) Filed: **Jun. 28, 2002**

DESCRIPTION

(30) **Foreign Application Priority Data**

Dec. 28, 2001 (IT) RM2001O0304

FIG. 1 is a side view of a module for magnetic coupling, particularly for a toy, showing my new design, the appearance of the side opposite that of FIG. 1 being identical thereto; and,

(51) **LOC (7) Cl. 08-08**

FIG. 2 is a bottom plan view thereof, the top plan view being identical to FIG. 2.

(52) **U.S. Cl. D8/382**

The device whose design is claimed has a square cross-section with cylindrical heads.
